(57) **CLAIM**

The ornamental design for a set of interchangeable cutting implements, as shown and described.

DESCRIPTION

FIG. 1 is an exploded perspective view of the set of interchangeable cutting implements showing my new design;

FIG. 2 is a perspective view of a portion of the set in an assembled condition, shown separately for clarity of illustration;

FIG. 3 is a top plan view of FIG. 2;

FIG. 4 is a bottom plan view of FIG. 2;

FIG. 5 is a left side elevation view of FIG. 2;

FIG. 6 is a right side elevation view of FIG. 2;

FIG. 7 is a front elevation view of FIG. 2; and,

FIG. 8 is a rear elevation view of FIG. 2.

The broken lines are for illustrative purposes only and form no part of the claimed design.
